UNITED STATES PATENT OFFICE.

WILLIAM E. LEE, OF LONG PRAIRIE, MINNESOTA.

AEROPLANE.

1,121,262.

Specification of Letters Patent. Patented Dec. 15, 1914.

Application filed February 10, 1913. Serial No. 747,312.

To all whom it may concern:

Be it known that I, WILLIAM E. LEE, a citizen of the United States, residing at Long Prairie, in the county of Todd and State of Minnesota, have invented certain new and useful Improvements in Aeroplanes, of which the following is a specification.

My invention relates to improvements in aeroplanes, its object being particularly to provide means for maintaining equilibrium of the machine in flight and for righting the machine when the same is thrown out of balance.

To this end the invention consists in the features of construction, combination, and arrangement of parts hereinafter described and claimed.

In the accompanying drawings forming part of this specification, Figure 1 is a side elevation of a biplane fitted with my features of invention; Figs. 2 and 3 are detail views, broken away, of stabilizing wings or planes; Fig. 4 is a detail view, broken away, of one of the stabilizing wings and a co-operating locking device; Fig. 5 is a top view of a biplane fitted with my features of invention; and Figs. 6 and 7 are detail views of a locking device holding the stabilizing wings in extended position.

In the drawings is shown an ordinary construction of biplane, A representing the framework, 2 the overhead sustaining plane, and 3 the lower sustaining plane. The biplane is shown equipped with the usual lever mechanism 4 for the tilting of the sustaining planes and an engine 5 for actuating the propeller 6.

7 and 8 indicate the usual co-operating rudder and altitude planes.

In carrying out my invention, I provide stabilizing planes or wings B. In the arrangement shown I use a pair of these wings carried by shafts 9. The shafts have journal support 10 upon the top of the upper plane, said shafts extending longitudinally of the machine and alongside each other. The wings are adapted to be turned to lie flat upon the top of the plane 2 against the tension of the controlling springs 11, and are held in flat position, as by dogs 12 having fulcrum support 13 upon the top of the plane 2, cords 14 extending downwardly from the lower ends of the dogs to a point adjacent the aviator's seat 15, as shown. An opening 16 is formed in each wing so that

the co-operating dog may be turned over the edge of the wing, forming the opening, as shown in Fig. 4. A pull upon the cord of either dog will disengage that dog from the corresponding wing and allow said wing to be turned into upright position by its spring 11, as illustrated in dotted lines in Fig. 1.

In order to positively hold either wing in upwardly extending position, I provide the brackets 17 extending from the top sustaining plane 2 upwardly between the shafts of the wings B. Each bracket carries a cross bar 18 at its upper end with depressible dogs 19 in the cross bar upon opposite sides of the bracket, the dogs being carried by a spring strip 20 having central support 21. Thus, when either wing is released, its spring 11 will carry it to raised position past the corresponding dog 19, the dog being depressed by the wing as the same passes inward past the same, and then being forced outward by the supporting spring strip 20 to hold the wing locked between the dog and bracket. The opening 16 in the wing will allow the end of the cross bar 18 to pass through the wing when the same is carried to raised position, the edge 22 passing into position between the bracket and dog.

By means of my improved stability wings I am enabled, when the aeroplane begins to skid to one side or to tip, to release the wing upon that side, allowing the same to be carried by its spring to raised position to right the aeroplane.

While I have shown my features applied to the top sustaining plane of a biplane, I can equally well apply the same to a monoplane and may also apply them to the lower sustaining plane of the biplane.

I claim as my invention:

1. In combination with the sustaining plane of an aeroplane, a stabilizing wing supported upon a shaft extending longitudinally, and substantially in the center, of the machine, journal supports for said shaft upon the sustaining plane, means for locking said wing flat against the outer face of said plane, means for releasing said locking means from the aviator's seat, and spring means for carrying said wing into position extending outwardly substantially at right angles with the face of the plane.

2. In an aeroplane including a sustaining plane and aviator's seat, a stabilizing wing hinged upon said sustaining plane and ex-

tending longitudinally of the machine, a locking device for holding said wing in flat-wise position upon said sustaining plane, spring means for carrying said plane to extended position when released from said locking means, and means for locking said wing in extended position.

3. In an aeroplane including a sustaining plane and aviator's seat, a stabilizing wing having journal support upon said plane and extending longitudinally of the machine, a locking device for holding said wing in flat-wise position against said plane, means actuatable from the aviator's seat for releas-

ing said locking means, spring means for carrying said wing to extended position at right angles with the plane when said locking means are released, and means actuatable as said wing passes to extended position to coöperate with and lock the same in such position.

In testimony whereof I affix my signature in presence of two witnesses.

WILLIAM E. LEE.
